UNITED STATES PATENT OFFICE

ROBERT K. MATLACK, OF MILLTOWN, NEW JERSEY

SPRAYING DEVICE

Application filed September 9, 1930. Serial No. 480,760.

The present invention relates to methods of and devices for spraying material, and is particularly adapted to the distribution of fluids on a paper surface or a similar article. Such fluids may constitute any coating material, such as coloring, gumming, wax, glue, and other materials. The method and device of the invention are, however, not limited to the distribution of fluids, since they are applicable also to the distribution of any material which can be sprayed, such for example as material in a finely divided or powdered state.

It is the general object of my invention to provide a device of the class indicated which is simple in construction but highly efficient in operation, attaining results heretofore impossible with devices of the prior art.

A further object of the invention is to provide a device which operates in accordance with a novel method to obtain an extremely even coating of any desired thickness of material on the article to be coated. This object is attained by a method which comprises the expansion of compressed gaseous matter, such for example as compressed air, to equalize its pressure throughout, and the emission of the expanded gaseous matter from an elongated slot nozzle which extends the full width of the article being coated. In this manner, a stream of gaseous matter of even pressure throughout the entire stream is obtained and may be directed against particles of the material to be sprayed or distributed, forcing them on to the article being coated.

A device constructed in accordance with my invention and which operates in accordance with the above outlined method, comprises a plurality of concentrically arranged chambers having expanding nozzles therebetween, the outermost chamber having an elongated slot nozzle for emitting the expanded gaseous matter. While I have illustrated and described, hereinafter a single embodiment of my device which comprises only two concentrically arranged chambers, it will be apparent that any number of expanding chambers may be provided and, of course, the greater the expansion of the emitted matter,

the more even will be its pressure and application to the article being coated.

The above objects and features of my invention, as well as the details of construction of a single embodiment thereof, will be readily understood from the following detailed description taken in connection with the accompanying drawings.

In the drawings:

Fig. 1 is a view showing the specific embodiment of the device of my invention in side elevation, a portion of the containers being broken away to enable a clearer understanding of the details of the device.

Fig. 2 is a sectional view along line II-II of Fig. 1;

Fig. 3 is a view partly in section of one end of my device showing the details of construction thereof, especially the details of the adjustable feature of the outer concentric chamber; and

Fig. 4 is a sectional view along line 4-4 of Fig. 3.

Referring to the several views of the drawings, there is shown a horizontally disposed hollow shaft 1 which is fixedly mounted in supporting standards 3 and 4. The shaft 1 is provided with nozzles 2 which extend around a substantial part of its periphery in any desired arrangement (see Fig. 2). These nozzles may be formed as an integral part of the shaft, or they may comprise threaded members which are adapted to be screwed into threaded holes in the shaft. One end of shaft 1 is provided with a cap member 5, which may take form of a threaded member screwed on the end of the shaft. The purpose of this cap is to provide a gas-tight enclosure for the end of shaft 1. The other end of the shaft is attached to a valve 6, which may be of any desired form and whose purpose is to control the flow of compressed air, or other gaseous matter to the device. Shaft 1 is provided adjacent support 3 with a roller bearing 7, which may comprise a suitable housing or race members 8 and 9 (see Fig. 3) and suitable roller members 10. The purpose of this bearing is to provide a rotatable mounting for gear 11 on the hollow shaft. Gear 11 comprises a spider portion

and hub 12, the hub being adapted to fit over the outer housing of bearing 7. Suitable bearing spacers or collars on shaft 1 may, of course, be provided in the structure. Supporting standard 3 has its upper portion 5 formed to provide a journal or bearing housing 13 which receives shaft 14. One end of shaft 14 is provided with a pinion 15 which is adapted to mesh with gear 11 to drive the latter. The other end of shaft 14 may be connected to any suitable driving mechanism 10 having the desired speed and speed control means.

The peripheral portion of gear 11 has an 15 extending flange 16 with spaced holes thereabout. A screen member 18, which in the present instance takes a cylindrical or squirrel cage form, has one end attached to the flange 16 by means of suitable bolts 17. The end of the screen member fits snugly over the 20 flange, and as many bolts as is necessary to provide a secure connection may be used. The other end of the screen member is attached to a spider member 19, which has an 25 extending flange 20 similar to flange 16 of the gear. In this case also the end of the screen fits snugly over the flange, and a plurality of bolts comprise the attaching or securing means. The spider 19 is mounted upon the 30 hollow shaft 1 by means of a suitable roller bearing 21, in the same manner as gear 11 is mounted thereon. In this instance also, suitable spacers or collars may be used if necessary. From the description thus far, it will 35 be apparent that pinion 15 being driven by some external source of power will drive the squirrel cage or screen member through the medium of gear 11, the screen member rotating on its bearings about the stationary 40 shaft 1.

Inside the screen member and adjacent the bearings which support the screen member, shaft 1 has mounted thereon a pair of eccentric members 22. Reference may be had to 45 Figs. 3 and 4 and a clearer understanding of the details of construction now to be described. The details of one end only of the device are shown since the other end is identical. The eccentric member 22 has an enlarged portion adjacent shaft 1 which is provided with a pair of diametrically opposite 50 threaded holes. A packing gland member 23 surrounds shaft 1 and is attached to eccentric 22 by means of a pair of threaded bolts 26 and 27 which are provided in extending ears 55 24 and 25 of member 23. Any suitable packing material may be used to provide a gas-tight joint. It will be understood that this 60 feature of the device is a conventional one which is well known in mechanical arts. Co-operating with eccentric 22 is an eccentric ring 28. A plurality of lugs 29, which are 65 adapted to be secured or attached to ring 28 by means of bolts 30 and nuts 31, adjustably 70 attach the eccentric to its co-operating ring.

It will be apparent that by loosening bolts 26 and 27, the eccentric is loosened so that it may be rotated about shaft 1. By loosening bolts 30, the eccentric is detached from its ring member 28, so that the eccentric may be 75 rotated, thereby varying the position of its co-operating ring. While the details of only one eccentric and its ring member are shown in Fig. 3, it will be understood that the construction at the other end of shaft 1 is identical therewith. Eccentric ring 28 is formed to have a peripheral flange 32, which has holes thereabout for the reception of screws 33. A cylindrical member 34 has peripherally arranged threaded holes at each end for the 80 reception of the screws 33. In this manner, member 34 may be securely attached to the eccentric ring members 28 at each end. This structure constitutes the outer expansion member of the device. Member 34 is provided longitudinally thereof with an elongated slot nozzle 35 which extends its entire length.

It will be apparent that while the screen or squirrel cage rotates about the stationary 85 shaft 1, the cylindrical member 34 within the screen member is stationary. By means of the adjustable feature shown, the position of member 34 may be varied with respect to the hollow shaft. This also varies the position 90 of member 34 and its nozzle 35 with respect to the rotating screen. A container 36 is provided, as shown in Fig. 2, for the material 95 to be sprayed or distributed. This container is disposed underneath the rotating screen member, and may be provided if desired with an overflow tray 37.

In operation, the rotating screen will lift 100 particles of the material from the container 36 and will carry them adjacent the slot nozzle 35, where they will be blown off the screen onto the article being coated. It will be understood, of course, that the article being 105 coated, such for example as paper, may be mounted on rotating rolls arranged and driven in any suitable manner so as to cause the paper to pass adjacent the nozzle and screen at a constant speed. The compressed gas, air for example, will pass through the stationary shaft 1 and from there into the outer 110 chamber through the nozzles. In doing so the gas is expanded to such a degree that its pressure is uniform throughout.

A device constructed in accordance with 115 my invention possesses many desirable features. It will be noted that the thickness of the coating being distributed or sprayed on the particular article may be regulated in several ways. The speed of the rotating 120 screen member may be adjusted by suitable regulating means. The speed of this member will partly determine the thickness of the coating being applied. Furthermore, the speed of the screen member may be adjusted 125 to suit coating materials of different consist- 130

encies. For example, a material of light consistency would be more readily projected from the screen onto the paper than a material of heavier consistency, and, therefore, different speeds of the rotating screen member would be required to give coatings in each case of the same thickness. It will also be apparent that the coating of the material will depend upon the distance of nozzle 35 from the screen member. By means of the adjustable feature shown, the outer cylindrical chamber may be adjusted both horizontally and vertically, thereby varying the position of the emitting nozzle with respect to the screen. The coating may also be varied by varying the pressure of the incoming gas. It is to be understood that any number of expansion chambers may be provided. While I have shown a single embodiment having 20 expanding nozzles for conveying the compressed gaseous matter from an inner chamber to an outer expansion chamber, it will be apparent that a greater number of concentric members having expanding nozzles for 25 conveying the compressed gas from one chamber to the next may be provided. In this instance, of course, only the outermost chamber would be adjustable. My invention contemplates broadly the idea of expanding the gas 30 in a series of concentric chambers before finally emitting it from an elongated nozzle provided on the outer member. It is also to be understood that various other ways than that shown may be used for conveying the material to be sprayed from its container to a point adjacent the nozzle. For example, instead of using a squirrel cage member, a screen conveyor could be mounted for rotation about a plurality of rotating rollers so 40 that it would pass the nozzle. Another modification would be to have a plurality of tangentially arranged rollers for picking up the material from its container, and have the nozzle blow the material from the surface of 45 such rollers.

It is, therefore, to be understood that my invention is not limited to the single embodiment disclosed and described herein. The above-indicated and other modifications of 50 the device will be readily apparent to those skilled in the art without departing from the spirit and scope of the invention. I desire it to be understood, therefore, that my invention is not to be limited by the specific disclosure herein contained but only as is necessary in view of the prior art as indicated in the scope of the appended claims.

I claim:

1. In a spraying device for coating paper 60 or the like, means for supplying compressed gaseous matter to said device, means for expanding said matter to obtain uniform pressure thereof, means for carrying the material to be sprayed, means for directing an even 65 stream of said matter against said carrying

means to project said material in a finely divided state on to the article to be coated and means for moving said directing means toward and away from said carrying means.

2. In a spraying device for coating paper 70 or the like, means for supplying compressed gaseous matter to said device, pressure expanding means for said matter comprising a plurality of intercommunicating expansion chambers, means for carrying the material to be sprayed, and means for directing a wide and even stream of said matter against said carrying means to project said material in a finely divided state on to the article to be coated. 75

3. In a spraying device for coating paper 80 or the like, means for supplying compressed gaseous matter to said device, pressure expanding means for said matter comprising a plurality of concentrically arranged chambers having pressure expansion nozzles for the passage of said matter therebetween, the outermost chamber having an elongated slot nozzle for the emission of said matter in a wide and even stream, and means for carrying particles of the material to be sprayed to a point adjacent said nozzle, whereby the emitted matter blows said material off said carrying means on to the article to be coated. 85

4. In a spraying device for coating paper 90 or the like, a hollow shaft serving as a conduit for compressed gaseous matter, a plurality of nozzles spaced about a substantial portion of the cylindrical surface of said shaft, a cylindrical member adjustably 100 mounted on said shaft and enclosing said nozzles to form an expansion chamber for said matter, said member having an axially disposed elongated slot nozzle for the emission of said matter, a container disposed beneath said nozzle, and rotatable means for 105 lifting particles of material from said container to a point adjacent said nozzle, whereby said material may be blown on to the article to be coated. 110

5. In a spraying device for coating paper 115 or the like, a hollow shaft serving as a conduit for compressed gaseous matter, a plurality of nozzles spaced about a substantial portion of the cylindrical surface of said shaft, a cylindrical member adjustably mounted on said shaft and enclosing said nozzles to form an expansion chamber for said matter, said member having an axially disposed elongated slot nozzle for the emission of said matter, a container disposed beneath said nozzle, and a screen member 120 mounted for rotation about said shaft and adapted to lift particles of material from said container to a point adjacent said nozzle, whereby said material may be blown on to the article to be coated.

6. In a spraying device for coating paper 125 or the like, a hollow shaft serving as a conduit for compressed gaseous matter, a plurality 130

of nozzles spaced about a substantial portion of the cylindrical surface of said shaft, eccentric members carried by said shaft, a cylindrical member enclosing said nozzles to form an expansion chamber for said matter, eccentric rings carried by said cylindrical member and cooperating with said eccentric members, whereby said cylindrical member is vertically and horizontally adjustable relative to said shaft, said cylindrical member having an axially disposed elongated slot nozzle for the emission of said matter, a container disposed beneath said nozzle, and rotatable means for lifting particles of the material from said container to a point adjacent said nozzle, whereby said material may be blown on to the article to be coated.

ROBERT K. MATLACK.
